BURNER CONTROL SYSTEM

John J. Rothwell, Elkhart, and Leland B. Wagner,
Goshen, Ind., assignors to Penn Electric Switch
Co., Goshen, Ind., a corporation of Iowa

Application February 10, 1941, Serial No. 378,150

6 Claims. (Cl. 158—28)

Our invention relates to a burner control system wherein a combustion switch has a temperature responsive element responding directly to combustion chamber temperature and has a safety feature, the arrangement being such as to eliminate the necessity of the usual "slip" or "friction" connection used in present day "stack switches."

One object of our invention is to provide a combined combustion switch and safety switch which may be connected in a burner control circuit so as to de-energize the circuit as a result of combustion failure initially, combustion failure after establishment, or failure of a safety heater, such as a burnt-out condition thereof.

Another object is to provide a combustion switch which is extremely simple in construction and inexpensive to manufacture and which may be arranged to respond to combustion by exposing a certain bimetal element of the combustion switch to heat radiated from the combustion chamber, it being unnecessary to locate the thermostat inside a stack or the like nor inside the combustion chamber, but merely externally of the chamber with an opening through the wall of the chamber to expose the bimetal element to the heat therein.

A further object is to provide a modified form of combustion switch in our burner control system which locks out instead of recycling after a flame failure occurs.

Still a further object is to provide a burner control system including a combustion switch which may be connected in either low voltage control circuits or high voltage main circuits of different burner systems and which will operate in its intended manner under the influence of a wide variation of conditions.

With these and other objects in view, our system consists in the construction, arrangement and combination of the various parts thereof whereby the objects contemplated are attained, as hereinafter more fully set forth, pointed out in our claims and illustrated in the accompanying drawing. Although our system is susceptible of a variety of embodiments, it is unnecessary to fully describe and illustrate more than a few in order to give a full understanding of the system both from structural and functional standpoints. Accordingly, we have illustrated a preferred and desirable embodiment thereof in the accompanying drawing, in which

Figure 1 is an electrodiagrammatic view of a burner control system embodying our invention and showing it adapted to a system having a low

voltage room thermostat or control circuit, the combustion switch being shown in cold position;

Figures 2, 3 and 4 show respectively the combustion switch in hot, initial combustion failure, and combustion failure after established, positions;

Figure 5 is a diagrammatic view of a portion of Figure 1 showing a slight modification;

Figure 6 is a diagrammatic view showing our system applied to an all high voltage circuit; and

Figure 7 is a view similar to Figure 3 showing a modified construction.

On the accompanying drawing, we have used the reference character BM to indicate a burner motor, and Ign the ignition mechanism for the burner. A motor switch MS controls energization of the burner motor and the ignition mechanism, with current being supplied through line wires 18 and 20. The wires 18 and 20 also extend to the primary P of a transformer T.

A room thermostat RT is illustrated and a low voltage circuit therefor is energized from the secondary S of the transformer T. The secondary circuit includes a relay coil RC and a safety heater H, together with combustion switch contacts 14 and 15.

The combustion switch for the contacts 14 and 15 is indicated generally at CS and includes a pair of bimetal elements 10 and 12 anchored as 30 to a support 18 of insulating material. The contacts 14 and 15 are carried by the bimetal elements 10 and 12, respectively. The bimetal element 10 carries a support 18 for a permanent magnet 17 which is adapted to cooperate, for a 35 purpose which will hereinafter appear, with an armature 18. The armature 18 is carried by the bimetal element 12. The combustion switch CS is preferably mounted just outside a combustion chamber CC with an opening 11 in the wall of 40 the chamber to permit radiation of combustion heat to the element 10.

As shown in Figure 5, the effect of the heater H on the bimetal element 12 may be somewhat varied, as by interposing a rheostat R in the room 45 thermostat circuit. We have found in actual practice, however, that the combustion switch is not very critical, and in the usual run of installations the size and amount of resistance wire for the heater H can be readily predetermined.

Our burner control system is adaptable for all high voltage installations, as illustrated in Figure 6, wherein a room thermostat RT' is of the high voltage variety and acts as a main or motor switch for the burner motor BM. The heater H' 55 is of course somewhat heavier, to take care of the

heavier current flowing through the burner motor and yet secure approximately the same heating effect on the bimetal element 12 as is secured by the low voltage heater H of Figure 1 thereon. A limit control LC is illustrated in circuit with the burner motor, room thermostat and heater of Figure 6, as is usual in installations using high voltage room thermostats.

In Figure 7, we show a modified construction wherein a lock out latch 21 has been added to the combustion switch CS. The latch 21 is pivoted to the member 18 and normally assumes the dotted position illustrated when the parts are in the position of Figure 1 or when they are in the position of Figure 2. A spring 22 is provided to swing the latch 21 into a lock out position, shown by solid lines, whenever the contacts 14 and 15 are separated, as in Figure 3 or Figure 4. The burner system thereafter cannot recycle except after the end 23 of the latch 21 has been pushed upwardly manually for resetting the combustion switch.

PRACTICAL OPERATION

Normal burner operation

With the combustion switch in the cold position of Figure 1, closure of the room thermostat effects energization of the relay coil RC and the heater H through the combustion switch contacts 14 and 15 from the secondary S of the transformer T. Energization of the relay coil effects closure of the motor switch MS whereby the burner motor BM and the ignition mechanism Ign of the burner are energized.

Energization of the heater H causes the bimetal element 12 to be heated and thereby warped, but this is a relatively slow process. Accordingly the bimetal element 12 does not warp enough to separate the contact 15 from the contact 14 before combustion chamber temperatures start warping the bimetal element 10, so that the contact 14 follows up the contact 15. The magnet 17 and the armature 18 also aid in keeping the contacts 14 and 15 engaged. The bimetal elements 10 and 12 may be placed under some initial tension when mounted on the insulating block 13 if it is desirable to eliminate the armature and magnet.

Subsequently, when the room thermostat opens, the relay coil is de-energized to thereby open the motor switch and stop the burner. The parts 10 and 12 will then cool down to their initial positions, as in Figure 1, for another burner operating cycle.

Failure of combustion to be established

Referring to Figure 3, if combustion does not occur in the normal manner, the bimetal element 10 will remain in its cold position while the bimetal element 12 will move to its hot position, due to energization of the heater H. This will take preferably about a minute or so, although the time does not have to be as long as it takes the usual safety switch in a stack switch installation to trip out. The room thermostat circuit is now opened across the combustion switch contacts 14 and 15 so that the relay coil is de-energized, thus opening the motor switch.

After a time period predetermined by the length of time it takes the heater H and the bimetal element 12 to cool down, the control circuit will be reestablished, thus providing a purging period and thereafter permit an attempt at another start of the burner.

Combustion failure after combustion has been established

Referring to Figure 4, combustion has been established thus moving the parts of the combustion switch to the position of Figure 2 and then combustion has failed so that the bimetal element 10 begins to bend back toward its original position, due to cooling down of the combustion chamber. Accordingly, the contact 14 will leave the contact 15 when the energy built up by straightening of the bimetal element is sufficient to overcome the pull of the magnet 17 on the armature 18. The contacts 14 and 15 thereupon open with snap action. The relay coil is now de-energized, so that the motor switch opens and a purging period will be provided, during which the elements 10 and 12 cool to their initial position. The contacts 14 and 15 are thereupon re-engaged to recycle the burner.

The operation of Figure 5 is substantially the same as already described, the rheostat R being provided for the purpose of changing the heating value of the heater H so as to compensate for different conditions encountered in different installations. It is believed obvious how Figure 6 operates in substantially the same manner as Figure 1, with the burner motor current passing directly through the room thermostat and the heater.

The combustion switch we use in our burner control system is a combined combustion switch and safety switch in that the contacts 14 and 15 are separated as a result of a cold combustion chamber CC and a hot heater H. Whenever these two events occur at the same time, then the burner is shut down for a purging period and recycling. As long as the burner operates on normal cycles the contacts 14 and 15 remain engaged and are never separated. Separation occurs only when there is either an initial combustion failure or a combustion failure subsequent to combustion establishment.

In the operation of our combustion switch when constructed in accordance with Figure 7, a flame failure either initially, as in Figure 3, or after establishment, as in Figure 4, will result in the latch 21 assuming its lock out position, thus preventing a recycling of the burner until after the trouble has been remedied by a service man and he has reset the combustion switch.

Our arrangement is such that we have the combustion switch responsive to combustion chamber temperatures from a point exterior of the combustion chamber, where temperatures range only from 70° to 200° Fahr., whereas the temperature responsive element of a stack switch must withstand temperatures in the neighborhood of 700° Fahr. Our combustion switch entirely eliminates a slip connection and is so designed as to combine a warp type of safety switch with the combustion responsive element so as to use a single set of contacts instead of the usual arrangement of one set of contacts for the combustion temperature responsive element and another set for the safety switch. The movement of the bimetal elements from the position of Figure 1 to the position of Figure 2, it will be noted, causes the contacts 14 and 15 to wipe across each other, thus keeping them clean at all times.

We have found that rather wide variations in combustion chamber temperatures and heater temperatures do not materially affect operation of the combustion switch, and the bimetal elements 10 and 12 are able to keep in step during normal

burner operations, which vary over a wide temperature range in the combustion chamber. The bimetal elements get out of step, however, under any conditions of combustion failure and thus give the desired protection heretofore afforded by having a stack switch and a safety switch arranged in series with each other.

The usual style of stack switch has a greater tendency to trip out on "hot starts" than on "cold starts." Our arrangement has no tendency to trip out except when combustion fails and will respond equally fast on failures in either a hot or a cold furnace. Combustion failure is a function of only one thing, to-wit, heat of the heater H positioning the contact 15 at a predetermined position so that the contact 14 is either left behind or returns toward open position, as illustrated in Figures 3 and 4, respectively. The bimetal element 10 may become sooted up, but the operation of the combustion switch is substantially the same whether in a clean or sooted up condition. To minimize a variation in operating characteristics, the element 10 may be initially coated with a black substance.

As many changes could be made in the foregoing described system and many apparently widely different embodiments of this invention could be made without departing from the scope thereof, it is intended that all matter contained in the above description or shown in the accompanying drawing shall be interpreted as illustrative and not in a limiting sense. It is also to be understood that the language we use in the following claims is intended to cover all of the generic and specific features of the invention herein described and all statements of the scope of the invention which, as a matter of language, might be considered as falling therebetween.

We claim as our invention:

1. In a burner control system, a burner motor, an operating circuit therefor including a switch, means responsive to room temperature for effecting closure of said switch, a circuit for the room temperature responsive means having a combustion switch and a heating element connected serially therein, said combustion switch comprising a pair of bimetal elements, a contact carried by each of said bimetal elements, said contacts being engaged when said bimetal elements are cold, one of said bimetal elements being responsive to combustion chamber temperatures and the other one being responsive to heat from said heating element, said bimetal elements, when so responding, warping in the same direction and maintaining said contacts closed whereby heating of the heating element and a cooling or a cold condition of said combustion chamber effects separation of said contacts, an armature carried by one of said bimetal elements, a magnet cooperating therewith and carried by the other bimetal element, said armature and said magnet tending to keep said contacts in engagement and effecting snap action thereof toward open position when the energy in said bimetal elements is such as to overcome the pull of the magnet on the armature.

2. In a burner control system, a burner motor, an operating circuit therefor including a switch, means responsive to room temperature for effecting closure of said switch, a circuit for the room temperature responsive means having a combustion switch and a heating element connected serially therein, said combustion switch comprising a pair of bimetal elements, a contact carried by each of said bimetal elements, one of said bi-

metal elements being responsive to combustion chamber temperatures and the other one being responsive to heat from said heating element, an armature carried by one of said bimetal elements, a magnet cooperating therewith and carried by the other bimetal element to keep said contacts in engagement and effect snap action thereof toward open position when the energy in said bimetal elements is such as to overcome the pull of the magnet on the armature.

3. In a burner control system, a burner motor, a switch for operating said burner motor, means responsive to room temperature for effecting closure of said switch, a control circuit controlled by said room temperature responsive means and having a combustion switch and a heating element connected serially therein, said combustion switch comprising a pair of thermal elements, contacts controlled by said thermal elements and movable in direct proportion to movement of said thermal elements, said contacts being engaged when said thermal elements are cold, one of said thermal elements being responsive to combustion chamber temperature and the other one being responsive to heat from said heating element, said thermal elements, when so responding, moving in the same direction with said contacts remaining closed, heating of said heating element and cooling or a cold condition of said combustion chamber moving said thermal elements relatively away from each other and thereby effecting separation of said contacts, and snap acting means cooperating with said thermal elements and tending to keep said contacts in engagement and effecting snap action thereof toward open position when the energy in said thermal elements is such as to overcome the force of said snap acting means, said thermal elements, upon subsequent cooling of said heater, moving relatively toward each other and said snap acting means effecting the final engagement of said contacts with snap action.

4. In a burner control system, a burner motor, a switch for operating said burner motor, means responsive to room temperature for effecting closure of said switch, a control circuit controlled by said room temperature responsive means and having a combustion switch and a heating element connected serially therein, said combustion switch comprising a pair of thermal elements, contacts controlled by said thermal elements, one of said thermal elements being responsive to combustion chamber temperature and the other one being responsive to heat from said heating element, and means to effect snap action of said contacts to disengage each other after said thermal elements pass a critical position when moving away from each other and to effect snap action of said contacts to engage each other after said thermal elements pass a second critical position when moving toward each other.

5. In a burner control system, a burner motor, an operating circuit therefor including a switch, means responsive to room temperature for effecting closure of said switch, a circuit for the room temperature responsive means having a combustion switch and a heating element connected serially therein, said combustion switch comprising a pair of bimetal elements, a contact carried by each of said bimetal elements, said contacts being engaged when said bimetal elements are cold, one of said bimetal elements being responsive to combustion chamber temperatures and the other one being responsive to heat from said heating element, said bimetal elements, when so

responding, warping in the same direction and maintaining said contacts closed whereby heating of the heating element and a cooling or a cold condition of said combustion chamber effects separation of said contacts, an armature carried by one of said bimetal elements, a magnet cooperating therewith and carried by the other bimetal element, said armature and said magnet tending to keep said contacts in engagement and effecting snap action thereof toward open position when the energy in said bimetal elements is such as to overcome the pull of the magnet on the armature, and mechanical latch means to hold said contacts out of engagement when they snap to open position.

6. In a burner control system, a burner motor, an operating circuit therefor including a switch, means responsive to room temperature for effecting closure of said switch, a circuit for the room temperature responsive means having a combus-

tion switch and a heating element connected serially therein, said combustion switch comprising a pair of bimetal elements, a contact carried by each of said bimetal elements, one of said bimetal elements being responsive to combustion chamber temperatures and the other one being responsive to heat from said heating element, an armature carried by one of said bimetal elements, a magnet cooperating therewith and carried by the other bimetal element to keep said contacts in engagement and effect snap action thereof toward open position when the energy in said bimetal elements is such as to overcome the pull of the magnet on the armature, and latch means operable to hold said contacts out of engagement after snap action has occurred, said latch means being releasable to permit said contacts to reengage after said bimetal elements are both cold.
